UNITED STATES PATENT OFFICE

133,113

DESIGN FOR A THERMOMETER

Horace R. Whittier, Bristol, Conn., assignor to
The Cooper Oven Thermometer Company,
Pequabuck, Conn., a corporation of Connecticut

Application October 27, 1941, Serial No. 103,908

Term of patent 7 years

To all whom it may concern:

Be it known that I, Horace R. Whittier, a citizen of the United States, residing at Bristol, county of Hartford, State of Connecticut, have invented a new, original, and ornamental Design for a Thermometer, of which the following is a specification, reference being had to the accompanying drawing, forming part thereof.

Fig. 1 is a front elevational view of a thermometer, showing my new design; and

Fig. 2 is an edge elevational view thereof.
The pointer is lined for red and the annular band is lined for silver.

I claim:
The ornamental design for a thermometer, substantially as shown and described.

HORACE R. WHITTIER.
